UNITED STATES PATENT OFFICE.

GLEN E. JOHNSON, OF SPOKANE, WASHINGTON.

SAFETY APPLIANCE FOR DOOR LOCKS.

Application filed August 19, 1921. Serial No. 493,519.

To all whom it may concern:

Be it known that I, GLEN E. JOHNSON, a citizen of the United States, residing at Spokane, in the county of Spokane and 5 State of Washington, have invented certain new and useful Improvements in a Safety Appliance for Door Locks; and I do hereby declare the following to a full, clear, and exact description of the invention, such as will 10 enable others skilled in the art to which it appertains to make and use the same.

The object of the invention is to provide a comparatively simple and efficient means for securing doors or door locks against sur- 15 ceptitious opening or operation as for example for the protection of the occupant of a hotel or apartment room when it is desired to protect against intrusion from the outside, and for the protection of unoccupied 20 buildings which must be left otherwise un-protected and which must be secured from the outside; and in this connection to pro- 25 vide a safety device which will operate effectively even in the event that the ordinary door locking means should be out of order; and with these objects in view the invention consists in a construction and com- 30 bination of parts of which a preferred em- bodiment is shown in the drawing, wherein:

Figure 1 is a perspective view of a safety device embodying the invention applied in the operative position to a door.

Figure 2 is a sectional view of the same taken perpendicular to the plane of the 35 door.

Figure 3 is a rear view of the device de- tached and showing the members of the re- 40 tainers in the open or spread position.

Figure 4 is a detail view of one of the 45 retainer or knob engaging members de- tached.

Figure 5 is a similar view of the adjust- able key blank or pin carrier detached.

The device consists essentially of a re- 50 tainer 10 consisting of relatively movable members 10^a and 11^a which are adapted to form a casing or housing for a door knob 11, said retainer members being provided with base plate members 12, integral with which 55 they may be formed, said base plate members being pivotally connected at 13 to permit of the opening of the retainer as shown in Figure 3 to fit the same over a knob. The base plate members are also provided with means whereby they may be secured in the normal 60 position to hold the knob enclosing portion

thereof closed and hence in housing relation with the knob, and in the construction illustrated said holding means is provided by forming the free ends of the base plate mem- 60 bers with upturned ears 13 having regis- trable openings 14 for engagement by the shackle of a padlock 15 of any suitable key actuated or combination controlled type.

Connected with the retainer and more 65 preferably with the base member of the same through the medium of a carrier 16 is a key blank or pin 17 which may if pre- 70 ferred consist of a key which is adapted to be inserted into the key hole of the door lock and extended through the door so as to bar or block any attempt to insert a key from the other side thereof, said carrier ob- 75 viously preventing the insertion of the key from the side occupied by the retainer. In 80 the construction illustrated the carrier con- sists of a slotted plate 19 operating in a slot 20, so that the carrier may be adjusted lon- gitudinally of the base or bearing members 85 of the retainers to locate the key blank or pin in registration with the key hole of the door lock even though the distance between the same and the knob may slightly vary from the standard distance.

The key blank or pin in the construction 85 illustrated is provided with a transverse pivot 22 mounted in coiled keepers 23 at the free end of the carrier, but it will be understood that this construction may be varied and that the key of the lock in con- 90 nection with which the device is to be used may be substituted for the key blank or pin. A key blank is preferably used how- 95 ever rather than a straight pin, for the rea- son that it may be inserted through the key hole until the ward is beyond the other side of the door and then given a quarter turn so as to have the ward bear against the inner surface of the door to act as an addi- 100 tional means of insuring the security of the device in its application to the door knob.

An advantage of the device in addition to that of preventing access to the key hole of the lock and hence the unlocking of the door from either side until the device has 105 been removed, consists in the fact that if applied to a door for example of an unen- tanted house in which the bolt mechanism has become injured or is out of order, the re- 110 tainer will prevent the turning of the knob of the door from the outside and hence prevent the opening of the door even though

it may not be locked. The retainer cannot be turned by reason of the engagement of the key blank or pin with the key hole, and the knob being entirely concealed and housed within the casing or housing of the retainer is inaccessible.

Having thus described the invention, what I claim is:

1. A safety appliance for door locks having a knob embracing and engaging retainer and a key blank or pin connected therewith for extension through the key hole of the lock, the retainer having pivotally connected members adapted to enclose and house the door knob.
2. A safety appliance for door locks having a knob embracing and engaging retainer and a key blank or pin connected therewith for extension through the key hole of the lock, the retainer having knob concealing members provided with pivotally connected base plates and means for securing the members in their closed and knob embracing relation.
3. A safety appliance for door locks having a knob embracing and engaging retainer and a key blank or pin connected therewith for extension through the key hole of the lock, the retainer having knob concealing members provided with pivotally connected base plates and means for securing the members in their closed and knob embracing relation, and consisting of upturned extremities of the free ends of said base plate provided with registrable openings for engagement by the shackle of a pad lock.
4. A safety appliance for door locks having a knob embracing and engaging retainer

and a key blank or pin connected therewith for extension through the key hole of the lock, the key blank or pin being connected with the retainer.

5. A safety appliance for door locks having a knob embracing and engaging retainer and a key blank or pin connected therewith for extension through the key hole of the lock, said key blank or pin having an adjustable connection with the retainer.

6. A safety appliance for door locks having a knob embracing and engaging retainer and a key blank or pin connected therewith for extension through the key hole of the lock, a connection between the key blank or pin and the retainer consisting of a carrier having a slot and pin connection with the retainer for adjustment radially with relation to the knob.

7. A safety appliance for locks having a retainer to house an operating element of the lock, the appliance having means to enter a keyhole of the lock to prevent insertion of a key, said retainer being loose on and movable independently of the element aside from said means, whereby movement of the appliance in the event of fracture of said means will be independent of the lock and element to prevent operation of the element.

In testimony whereof I affix my signature in presence of two witnesses.

GLEN E. JOHNSON.
